[57] **CLAIM**

The ornamental design for a fuse holder, as shown and described.

DESCRIPTION

FIG. 1 is a top plan view of a fuse holder in a closed position showing my new design;

FIG. 2 is a bottom plan view thereof;

FIG. 3 is a right side elevational view thereof in a partially open position;

FIG. 4 is a right side elevational view thereof, the left side being a mirror image;

FIG. 5 is a front elevational view thereof;

FIG. 6 is a rear elevational view thereof; and

FIG. 7 is a perspective view thereof in an open condition.

The fuse shown in broken lines in FIGS. 3 and 7 is for illustrative purposes only and forms no part of the claimed design.
